US0D1098986S

(12) **United States Design Patent** (10) **Patent No.:** **US D1,098,986 S**
(45) **Date of Patent:** **** Oct. 21, 2025**

(54) **TRIANGLE PEDAL ASSEMBLY**

(71) Applicant: **Foshan Wodi Automobile Technology Co., Ltd.**, Foshan (CN)

(72) Inventor: **Yuyi Ye**, Foshan (CN)

(73) Assignee: **Foshan Wodi Automobile Technology Co., Ltd.**, Foshan (CN)

(**) Term: **15 Years**

(21) Appl. No.: **29/990,968**

(22) Filed: **Feb. 26, 2025**

(51) LOC (15) Cl. **12-16**

(52) U.S. Cl.

USPC **D12/203**

(58) **Field of Classification Search**

USPC D12/174, 203, 125; D15/14, 72; D17/99; D21/694; D24/179

CPC B60K 26/021; B62M 3/08; B62M 3/10; B60R 3/00; B60R 3/002; B60R 3/02; B60R 9/00; B60R 9/02; B60R 2013/046

(57) **CLAIM**

The ornamental design for a triangle pedal assembly, as shown and described.

DESCRIPTION

FIG. 1 is a front perspective view of a triangle pedal assembly, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view.

The broken lines in the drawings illustrate the portions of the triangle pedal assembly, which form no part of the claimed design.

1 Claim, 8 Drawing Sheets
